ATTORNEY

UNITED STATES PATENT OFFICE.

JAMES W. LINGARD, OF NEW YORK, N. Y.

PANTALOONS.

SPECIFICATION forming part of Letters Patent No. 225,399, dated March 9, 1880.

Application filed September 29, 1879.

To all whom it may concern:

Be it known that I, JAMES W. LINGARD, of the city, county, and State of New York, have invented a new and useful Improvement in 5 Pantaloons, &c.; and I do hereby declare that the following is a full, clear, and exact description of the same, reference being had to the accompanying drawings, and to the letters of reference marked thereon, making part of this 10 specification.

This invention is in the nature of an improvement in strengthening and re-enforcing the seams in and about the pocket-openings of pantaloons, overalls, &c.; and the invention 15 consists in pantaloons or overalls with a waistband divided at the hips into two parts, and with the pocket-openings faced within and at the mouth of the same by a continuous strip of cloth which bridges the lower part of 20 the pocket-opening, and which unites the lower part and the two sides of the pocket-opening, in combination with a bridge-piece which spans the seam at the junction of the strip of cloth and the pantaloons, all as hereinafter more 25 particularly described, as a new article of manufacture.

In the accompanying sheet of drawings, Figure 1 is a perspective view of pantaloons with my invention applied to the pocket and 30 side slit; Fig. 2, an edge view of my re-enforcing and facing strips, and Fig. 3 perspective view of same.

Similar letters of reference indicate like parts in the several figures.

35 A represents a pair of pantaloons or overalls with the waistband thereof divided at the sides or hips into two parts, *a* and *b*, and with the pocket-opening *B* faced within and at the mouth of the opening by a strip of cloth, 40 *C*, which strip, commencing at or near the upper edge of the side *a* of the waistband, is carefully stitched to the band and within one side, *c*, of the pocket-opening, the stitching extending to a point, *d*, at or near the bottom *e* of 45 the pocket-opening, near which point the strip *C* is folded and left unstitched, forming a bridge, *f*, to the point *g* on the opposite side, *h*, of the pocket-opening, along the inner side 50 of which, and from the point *g*, the strip *C* is stitched to a point, *i*; thence the strip *C*

bridges the opening *B*, as at *j*, from the point *i* to the opposite side, *c*, of the opening, and to a point, *k*, on the portion *a* of the waistband to which it is stitched. From this point *k*, and stitched to the strip *C* up to a point, *l*, on said strip *C*, is a strip, *D*. This last-named strip extends across and bridges at *m* the space *m'* between the strip *C* and the pantaloons *A*, and is stitched at *n* on the opposite side, *b*, of the divided band. 55

By this construction of pocket-openings in pantaloons both sides of the pocket-opening are faced. The seam at the bottom of the pocket-opening is stayed or re-enforced, and the point of juncture or seam at the upper side 65 of the pocket-opening is likewise stayed and re-enforced, whereby they are greatly strengthened and tearing at those points prevented, while at the same time the re-enforcing strips provide the proper facing or finishing of the 70 garment at the pocket-openings.

It is obvious that the strip *C*, instead of extending entirely within the side *c*, may commence at the point *d* and extend within the side *h*; but in this case a separate facing would 75 be required for the side *c*; and it is clear that, instead of the strip *D* being made of a separate piece to form the bridge *m*, the strip *C* may be so folded and applied as to form the bridge *m* without employing an additional strip for that 80 purpose.

The construction hereinbefore described for facing and staying pocket-openings of pantaloons is particularly applicable to pantaloons for children, in which the band is divided, as 85 above described, that they may be put on with facility, at which divided points they are liable to tear under ordinary circumstances, especially when being drawn on, as the foot of the child is apt to catch at those points immediately above the openings. 90

I am aware that it is not new to bridge the crotch of pantaloons at the fly with a check-piece of cloth or other inelastic pliable material, either separate from or in one piece with 95 the button-strip and button-hole strip, for the purpose of re-enforcing or strengthening the fly.

Having now described my invention, what I claim as new, and desire to secure by Letters Patent, is— 100

As a new article of manufacture, pantaloons with the waistband thereof divided at the hips, and with the pocket-openings thereof faced within and at the mouth of the same by a continuous strip of cloth, C, which bridges the lower part, e, of the pocket-opening, and which unites at j the two sides c and h of the pocket-opening, in combination with a bridge, D, which spans the seam at the junction i of the

strip C and the pantaloons A, substantially as to and for the purpose described.

In testimony whereof I have hereunto set my hand in the presence of two witnesses.

JAS. W. LINGARD.
